DESIGN FOR A CUTTER ELEMENT FOR FOOD CHOPPERS

Emery Earl Grow, Jacksonville, Fla.

Application October 25, 1937, Serial No. 72,422

Term of patent 3½ years

To all whom it may concern:

Be it known that I, Emery Earl Grow, a citizen of the United States, residing at Jacksonville, in the county of Duval and State of Florida, have invented a new, original, and ornamental Design for a Cutter Element for Food Choppers, of which the following is a specification, reference being had to the accompanying drawing, forming part thereof.

Figure 1 is a top plan view of a cutter element for food choppers, showing my new design.

Figure 2 is a side or edge elevational view thereof, and

Figure 3 is a longitudinal sectional view.

I claim:

The ornamental design for a cutter element for food choppers, as shown.

EMERY EARL GROW.
